ANODE SUPPLY SYSTEM

Sarkes Tarzian, Bryn Mawr, Pa., assignor to
Atwater Kent Manufacturing Company, Phila-
delphia, Pa., a corporation of Pennsylvania

Application September 13, 1933, Serial No. 689,302

9 Claims. (Cl. 250—27)

My invention relates to systems for supplying anode current to the tubes of radio apparatus from a commercial source of either direct or alternating current.

5 In accordance with my invention, switching means are provided which, for one position, affords voltage doubling when the source is of alternating current, and which, for another position, adapts the system for use with a direct current source; more particularly, it is characteristic 10 of the system that injury cannot result to any of its components if, with the switch in position for use with direct current, the system is connected to an alternating current source, or is improperly 15 poled in connecting to a direct current source; or if, with the switch in position for use with alternating current, it is connected to a direct current source.

Further, in accordance with my invention, in 20 changing over to direct current operation, the filter system is modified to reduce the voltage drop therein to offset the lack of voltage doubling.

My invention further resides in the features of 25 combination and arrangement hereinafter described and claimed.

For an understanding of my invention reference is to be had to the accompanying drawing in which:

Figure 1 illustrates diagrammatically an anode 30 power supply suited for use with either alternating or direct current;

Figs. 2 and 3 illustrate the circuit connections of the system of Fig. 1 as used for alternating and direct current sources, respectively.

35 Referring to Fig. 1, the system comprises a full wave rectifier FW, a filter F comprised of condensers C, C1, C2 and inductance S, and a switch 1 which is adapted to change the connections to accommodate the system for use with either a 40 direct current source or an alternating current source of supply.

The rectifier consists of anode *a* and cathode *c* which form one pair of unlike elements, and anode *a*1 and *c*1 forming a second pair of unlike 45 rectifier elements. In the specific type illustrated, both pairs of elements are included in a common envelope or tube, although it is to be understood that my invention is applicable for use when the rectifiers are individual tubes or individual rectifiers of other types. The cathodes *c*, *c*1, in the specific arrangement shown, are heated to suitable emission temperature by the heaters *h*, *h*1, which are adapted to be connected across the supply line in series with each other and in series 50 with the heaters *h*2—*h*4 of the tubes V, V1, V2,

etc., of the radio receiver whose anode current is to be supplied by the system.

When the switch 1 is thrown to the left to fit the system for operation from an alternating current source, the connections are as shown more clearly in Fig. 2. The supply or input conductor 2 is connected to the cathode *c*1 and anode *a*, and the other supply or input conductor 3 is connected between the condenser C, C1 cathode *c* is connected to the positive output conductor 4 and the anode *a*1 is connected to the negative output conductor 5, and all the inductance S, which may be the field winding of a dynamic speaker, is included in the negative conductor between the anode *a*1 and the output terminal B—. The voltage drop in the speaker winding may be used for biasing the grids of any one or more of the tubes V, V1, etc., and if the total voltage drop is too high, the inductance may be tapped as at T for the grid-biasing conductor GB. The aforesaid connections between the rectifiers and condensers C, C1 afford voltage doubling in a manner, per se, known to the art. To give a specific example, the rectifier FW may be a rectifier tube of the type 25Z5, having low internal impedance. With the supply conductors 2, 3 connected to alternating current source of 110 volts, the voltage across each of the condensers will be approximately 120 volts, and assuming that the resistance of the field winding S is about 2500 ohms, and the load current of the receiver about 40 milliamperes, the output voltage across the condenser C2 is about 140 volts. The tap T may be at such point that the drop of potential across the section *s* of the speaker is about 15 volts, which is suitable for 80 grid-biasing purposes.

If, with the switch in the AC position, affording the connections in Fig. 2, the supply conductors 2, 3 are plugged into a 110-volt direct current source, no injury will result since the condenser C is in series with the source and no rectified current is available. A direct current path could be provided by short-circuiting condenser C, but there are two serious objections to this simple expedient. If the supply conductor 2 95 were connected to the positive pole of the source or line LL, the circuit would function, but at low efficiency, because of the large voltage drop across the speaker field S. On the other hand, if the supply conductors 2 and 3 are connected to the negative and positive terminals, respectively, of the direct current supply source, heavy current will flow within the tube from anode *a*1 to cathode *c*1, which are now connected directly across the line; and since the tube is of low impedance, 105 110

it would be destroyed by the excessive current flow.

In accordance with my invention, voltage doubling is effected by the circuit shown in Fig. 2 when the switch 1 is in its left-hand position, Fig. 1; and when the switch is thrown to the right for direct current operation, the negative output conductor 5 is connected directly to the supply conductor 3, (Fig. 3). If the supply conductors 2, 3 are connected to the source properly, the current flows from the anode *a* to the cathode *c* to the output conductor 4. The current returns from the external circuit through the negative conductor 5 to the supply conductor 3. If, on the other hand, supply conductors 2, 3 are improperly poled, so that the anode *a* is negative, there is no direct current path, and the receiver is simply inoperative until the supply conductors are reversed. By shifting the connection of the negative output conductor 5 from the anode *a* to the supply conductor 3, it is ensured that there is only one direct current path through the tube between the supply conductors.

The second difficulty arising if C, Fig. 2, is shorted out to produce a direct current path, that of excessive voltage drop in the speaker field when the source of current is direct, is overcome by eliminating the voltage drop due to the section *s*₁ of inductance *S* when the receiver is to be used with a direct current source. If the inductance *S* were simply a filter choke, this could be effected by shunting out this section but, as in the particular arrangements shown, section *s*₁ is part of the speaker field, this is not feasible because the excitation would be too low. Instead, the section *s*₁, as shown in Fig. 3 is connected across the output conductors so that part of the excitation of the speaker field is due to current which traverses the section *s* in returning from the external or receiver circuit, and part is due to current directly through *s*₁. The only voltage drop, insofar as the external circuit is concerned, is that due to the section *s*, and the output voltage is suitably high for satisfactory operation.

Referring again to Fig. 1, the system there shown has the advantage that the user of the set need not know before hand whether the available power source is alternating or direct, and if direct, what the poling may be. The switching system is not only simple, but foolproof, in that, insofar as damage to the apparatus is concerned, the position of switch 1 is of no consequence and the set may be plugged into an alternating current or a direct current line of either polarity. If the switch 1 is in the alternating current position and there is no sound from the loud speaker when the supply conductors are connected to line *LL*, it follows that the source is of direct current and accordingly the switch 1 is thrown to the direct current side; and if the set is still silent, the supply conductors 2, 3 are reversed to obtain proper poling. If the switch is in the direct current position and the reproduction is weak and accompanied by loud hum, the switch is thrown to the AC position. At the same time that the connections between the output conductors and the rectifier circuit are changed, the speaker field sections are properly connected to obtain suitable output voltage.

While I have illustrated a preferred arrangement, it is to be understood that my invention is not limited thereto but is co-extensive in scope with the appended claims.

What I claim is:

1. A system for supplying anode current from

a source of alternating current or a source of direct current comprising a full-wave rectifier having two pairs of unlike elements, condensers connected in series between unlike elements of separate pairs of said rectifier, input conductors connected respectively to a point between said condensers and to other unlike elements of said rectifier, and switching means for connecting output conductors across said condensers in series for voltage doubling when said input conductors are connected to an alternating current source, and alternatively for connecting said output conductors to said point and to one of said first rectifier elements when said input conductors are connected to a source of direct current. 90

2. A system for supplying anode current from a source of alternating current or a source of direct current comprising a full-wave rectifier having two pairs of unlike elements, condensers connected in series between unlike elements of separate pairs of said rectifier, input conductors connected respectively to a point between said condensers and to other unlike elements of said rectifier, output conductors, an impedance having substantial resistance, and switching means for connecting said output conductors across said condensers in series for voltage doubling when said input conductors are connected to an alternating current source, and simultaneously to connect said impedance in one of said output conductors 100 to produce a substantial drop of the output voltage, and alternatively for connecting said output conductors to said point and to one of said first rectifier elements when said input conductors are connected to a source of direct current, and 110 simultaneously to reduce the drop of output voltage effected by said impedance.

3. A system for supplying anode current from a source of alternating current or a source of direct current comprising a full-wave rectifier having two pairs of unlike elements, condensers connected in series between unlike elements of separate pairs of said rectifier, input conductors connected respectively to a point between said condensers and to other unlike elements of said rectifier, output conductors, a speaker field winding having substantial resistance, and switching means for connecting said output conductors across said condensers in series for voltage doubling when the input conductors are connected 125 to an alternating current source and simultaneously connecting said field winding in series with one of said output conductors, and alternatively for connecting said output conductors to said point and to one of said first rectifier elements when said input conductors are connected to a source of direct current, and simultaneously to connect said field winding between said output conductors. 130

4. A system for supplying anode current for 135 radio apparatus from a source of alternating current or a source of direct current comprising a full-wave rectifier having two pairs of unlike elements, condensers connected in series between unlike elements of separate pairs, of said rectifier, input conductors connected respectively to a point between said condensers and to other unlike elements of said rectifier, output conductors one of which is connected to one of said first pair of rectifier elements, and switching means 140 for connecting another output conductor to said point for operation from a direct current source, or to the other of said first rectifier elements for operation from an alternating current source. 145

5. A system for supplying anode current for 150

radio apparatus from a source of alternating current or a source of direct current comprising a full-wave rectifier having two pairs of unlike elements, condensers connected in series between unlike elements of separate pairs of said rectifier, input conductors connected respectively to a point between said condensers and to other unlike elements of said rectifier, output conductors one of which is connected to one of said first rectifier elements, a speaker field winding, switching means for connecting another output conductor to said point for operation from a direct current source, or to the other of said first rectifier elements for operation from an alternating current source, and switching means operable simultaneously with said first switching means for including said speaker field in one of said conductors when the source of supply is alternating current, and for connecting it between said output conductors when the source of supply is direct current.

6. A system for supplying anode current for radio apparatus from a source of alternating current or a source of direct current comprising a full-wave rectifier having two pairs of unlike elements, condensers connected in series between unlike elements of separate pairs of said rectifier, input conductors connected respectively to a point between said condensers and to other unlike elements of said rectifier, output conductors one of which is connected to one of said first rectifier elements, a divided speaker field winding, switching means for connecting another output conductor to said point for operation from a direct current source, or to the other of said first rectifier elements for operation from an alternating current source, and switching means operable simultaneously with said first switching means for including said speaker field in the negative output conductor when the source of supply is alternating current, and for transferring part of the speaker field winding between said output conductors when the source of supply is direct current.

7. A system for supplying anode current for radio apparatus from a source of alternating current or a source of direct current comprising a full-wave rectifier having two pairs of unlike elements, condensers connected in series between unlike elements of separate pairs of said rectifier, input conductors connected respectively to a point between said condensers and to other unlike

elements of said rectifier, a positive output conductor connected to the cathode element of said first rectifier elements, a speaker field winding, and switching means for connecting said winding between the anode elements of said first rectifier elements and the negative output terminal of the system for operation when the source of supply is alternating current, and for connecting part of the speaker field winding between said point and the positive output conductor and another part of said field winding between said point and the negative output terminal for operation when the source of supply is direct current.

8. A system for supplying anode current for radio apparatus from a source of alternating current or a source of direct current comprising a full-wave rectifier having two pairs of unlike elements, an input conductor connected to unlike rectifier elements of separate pairs, condensers connected in series between other unlike rectifier elements, a second input conductor connected between said condensers, an output conductor connected to one of said second named rectifier elements, and switching means for connecting the other output conductor to said second supply conductor for operation when the source is direct current, and for connecting it to the other of said second named rectifier elements when the source is alternating current.

9. A system for supplying anode current for radio apparatus from a source of alternating current or a source of direct current comprising a low impedance rectifier having two anodes and two cathodes, a supply conductor connected to one of said anodes and one of said cathodes, a filter system, condensers connected in series between the other of said anodes and the other of said cathodes, a supply conductor connected to a point between said condensers, and switching means manually operable to one position to connect the input conductors of said filter system across said condensers in series to effect voltage doubling if said source is alternating current and to prevent injury to the rectifier if said source supplies direct current, and operable to another position to connect said filter input conductors across one of said condensers to provide a direct current path through the rectifier if said source is of direct current and properly poled, and to prevent injury to the rectifier if the source is improperly poled direct current.
